[57] **CLAIM**

The ornamental design for a toilet seat lifter, as shown and described.

DESCRIPTION

FIG. 1 is a perspective view of a toilet seat lifter showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof, taken along line 7—7 of FIG. 4; and,

FIG. 8 is a top plan view thereof, taken along line 8—8 of FIG. 4.

The broken line representation of a toilet and toilet seat in FIG. 1 is for illustrative purposes only and forms no part of the claimed design.
